Patented Oct. 14, 1919.

FIG. 2.

FIG. 4.

FIG. 3.

Inventor
Arthur W.F. Stenzel,
By his Attorneys
Edgar F. Stenzel

UNITED STATES PATENT OFFICE.

ARTHUR W. F. STENZEL, OF NEW YORK, N. Y.

SCREW-MACHINE.

1,318,510.

Specification of Letters Patent. Patented Oct. 14, 1919.

Application filed January 10, 1919. Serial No. 270,511.

To all whom it may concern:

Be it known that I, ARTHUR W. F. STENZEL, a citizen of Germany, and residing at New York, in the county of New York and State of New York, have invented certain new and useful Improvements in Screw-Machines, of which the following is a specification, such as will enable those skilled in the art to which it appertains to make 10 and use the same.

This invention relates to what are known as screw machines, or machines which employ a screw shaft for adjusting the position of the tool holder slide used therein; and the 15 object of the invention is to provide means whereby the exact extent to which the shaft must be turned in order to secure the desired adjustment of the tool holder slide may be determined and indicated on a suitable indicating dial or gage device, and all guess 20 work as to the extent of the movement of said shaft in order to secure such adjustment, or all movements of said shaft in order to accomplish such adjustments in 25 which the operator is guided only by his opinion are obviated; and with these and other objects in view the invention consists in the construction, combination and arrangement of parts hereinafter described 30 and claimed.

The invention is fully disclosed in the following specification, of which the accompanying drawing forms a part, in which the separate parts of my improvement are designated by suitable reference characters in 35 each of the views, and in which;

Figure 1 is a central longitudinal section of a part of a screw machine and showing a sectional view of my improved indicator 40 vice;

Fig. 2 a plan view of part of the construction as shown in Fig. 1;

Fig. 3 a partial section on the line 3—3 of Fig. 1; and,

Fig. 4 a detail of a part of the screw shaft employed.

In Fig. 1 of the drawing, I have diagrammatically indicated at 5 the framework of what is known as an automatic screw machine and at 6 I have indicated in dotted lines a tool holder slide carrying a tool holder or tool post 7, and connected with the tool holder slide 6 is the usual threaded shaft 8 which, in the practice of my invention, passes through a hollow box-shaped portion 9 on the frame 5 of the machine or

through the end members 10 of said box-shaped portion.

It will be understood that the frame 5 and tool holder slide 6 as well as the shaft 8 60 may be of the usual or any desired form and construction but I preferably employ the hollow box-shaped portion 9 at the top of the frame to provide a chamber or compartment 11 through which a thread-like gear 65 12 secured to the shaft 8 approximately, centrally thereof is free to pass. The gear 12 is made in the form of a thread the pitch of which corresponds to the pitch of the screw shaft 8 as is clearly illustrated in Figs. 70 1 and 4 of the drawing.

In practice I secure to the top of the box-shaped portion 9 of the frame 5, a cylindrical casing 13 having an elongated and reduced base portion 14 having a base flange 75 15 through which are passed screws or similar devices 16 for securing the casing 13 to the top of the box-shaped portion 9.

The bottom of the casing 13, or the elongated portion 14 thereof is open as shown at 80 17 in Fig. 3 of the drawing and the top of the casing 13 is closed by a transverse plate 18 having a raised externally threaded flange 19 on which is mounted an annular ring 20 between which and the top of the 85 flange 19 is placed a transparent disk 21 preferably composed of non-breakable material.

Rotatably mounted in the bottom of the elongated portion 15 centrally thereof is an 90 elongated gear or pinion 22 above which a shaft 23 is rotatably mounted in the casing 13 to which shaft is secured a gear 24 which meshes with the gear or pinion 22. Secured to the shaft 23 adjacent to the gear 24 is a 95 smaller gear 25 which meshes with a larger gear 26 secured to a shaft 27 rotatably mounted in the casing 13 above the shaft 23.

Rotatably mounted in the transverse top plate 18 of the casing 13 centrally thereof is 100 a stud 28 to the bottom of which is secured a disk 29 and to the top of which is secured a pointer arm 30. Secured to the disk 29, or the bottom face thereof, is an annular gear rack 31 with which, or in connection with 105 which, the gear 26 operates as clearly illustrated in Fig. 1 of the drawing.

The top face of the transverse top plate 18 is provided with a circularly arranged scale 32 having scale marks from 0 to 24 inclusive sub-divided by other scale marks, which indicate halves or fractions of the

scale marks 0 to 24 inclusive. In practice I preferably provide the free end of the screw shaft 8 with a thumb and finger piece 33 whereby said shaft may be rotated in the 5 usual manner.

From the foregoing description it is believed that my invention will be readily understood by those skilled in the art to which it appertains on a consideration of the 10 accompanying drawing and the following statement.

With the parts in the position shown in the accompanying drawing if it be desired to adjust the tool holder slide 6 in the direction of the arrow x two thousandths. The screw shaft 8 will be rotated in the direction of the arrow y in Fig. 1, which operation will rotate the gear or pinion 22 through the gear 12, which gear slides longitudinally of 15 the gear or pinion 22 in its operation, and the pointer or pointer arm 30 will be rotated through the gears 24, 25, 26 and rack 31 on the disk 29, and this operation will be continued until the pointer or pointer arm 30 20 moves from the position shown in full lines in Fig. 2 to that indicated in dotted lines in said figure, or to the numeral 2 on the scale 32 which indicates two thousandths.

If, however, it be desired to move the tool 30 holder slide 6 two thousandths in the direction of the arrow x^2 in Fig. 1, the screw shaft 8 will be rotated in the direction of the arrow y^2 , which operation will move the pointer or pointer arm 30 in the opposite direction from that above described, until it reaches the scale mark 23 which is two thousandths from the position of the pointer or pointer arm 30 as indicated in full lines in Fig. 2.

40 In other words my improved device indicates any desired adjustment of the tool holder slide 6 from one to twenty-five thousandths when the screw shaft 8 is rotated in the desired direction and the pointer arm 30 45 is rotated through the gears 12, 22, 24, 25 and 26 and the rack 31; the gear 12 slides longitudinally of the gear or pinion 22 in this movement as hereinbefore stated.

While I have shown certain details of construction for carrying my invention into effect and a specific gear arrangement for transmitting the movement of the screw shaft 8 to a suitable indicator, my invention is not limited to these details of construction 50 and various changes therein and modifications thereof may be made, within the scope of the appended claims, without departing from the spirit of my invention or sacrificing its advantages.

60 From the foregoing it will be understood that the casing 10 and the various parts thereof form a gage or indicating device which is operated when the tool holder slide 6 is adjusted through the screw shaft 8.

65 Having fully described my invention,

what I claim as new and desire to secure by Letters Patent, is:—

1. A machine of the class described, comprising a frame, a screw shaft mounted in said frame, a tool holder slide mounted in said frame and connected with one end of said shaft, an indicating device mounted on the frame in juxtaposition to said shaft and comprising a casing having a graduated dial in connection with which a pointer operates, 75 and means for gearing the pointer in connection with said shaft.

2. A machine of the class described, comprising a frame, a screw shaft mounted in said frame, a tool holder slide mounted in said frame and connected with one end of said shaft, a gear mounted on the screw shaft approximately centrally thereof, an indicating device mounted on the frame in juxtaposition to the gear on said screw shaft, 80 said device comprising a casing the bottom of which is open and the top of which is closed and provided with an annular scale, a pointer rotatably mounted in the top of the casing and adapted to operate in connection with said scale, and means for placing the pointer and the gear on the screw shaft 85 in operative connection.

3. A machine of the class described, comprising a frame, a screw shaft mounted in 95 said frame, a tool holder slide mounted in said frame and connected with one end of said shaft, a gear mounted on the screw shaft approximately centrally thereof, an indicating device mounted on the frame in 100 juxtaposition to the gear on said screw shaft, an elongated gear mounted in the bottom portion of the casing and in operative connection with the gear on the screw shaft, a pointer rotatably mounted in the top of the 105 casing and adapted to operate in connection with said scale, and other gears mounted in said casing and in operative connection with said elongated gear for rotating said pointer.

4. A machine of the class described, comprising a frame, a screw shaft mounted in said frame, a tool holder slide mounted in said frame and connected with one end of said shaft, a gear mounted on the screw shaft approximately centrally thereof, an 115 indicating device mounted on the frame in juxtaposition to the gear on said screw shaft, said device comprising a casing the bottom of which is open and the top of which is closed and provided with an annular scale, 120 a disk rotatably mounted in the top of the casing approximately centrally thereof and the bottom face of which is provided with an annular gear rack, a pointer arm connected with said disk and mounted on the upper 125 face of the top of the casing and adapted to operate in connection with said scale, an elongated gear rotatably mounted in the bottom portion of the casing and in operative connection with the gear on said screw 130

shaft and other gears rotatably mounted in the casing and adapted to place said elongated gear and said gear rack in operative connection whereby the rotary movement of the screw shaft will be transmitted to said pointer arm.

5. A machine of the class described comprising a frame provided with a box-shaped portion, a screw shaft mounted in said box-shaped portion, a tool holder slide mounted in said frame and connected with one end of said shaft, a thread-like gear mounted on the screw shaft within the box-shaped portion, an indicating device secured to the top of the box-shaped portion of the frame, said device comprising a cylindrical casing having a reduced elongated base portion the bottom or reduced portion of the casing being open and the annular or top portion of which is closed and provided with a detachable ring for securing a transparent

panel in place, the top of the casing being provided with an annular scale, a pointer arm rotatably mounted in the top of the casing and adapted to operate in connection with said scale and carrying a disk beneath the top of the casing, said disk being provided with an annular gear rack, an elongated gear mounted in the bottom portion of the casing and in operative connection 30 with the thread-like gear on the screw shaft, and other gears rotatably mounted in the casing and adapted to place said elongated gear and gear rack in operative connection.

In testimony that I claim the foregoing as 35 my invention I have signed my name in presence of the subscribing witnesses this 8th day of January, 1919.

ARTHUR W. F. STENZEL.
